Fig. 6

Fig. 7

Fig. 8

FIG. 1 is a front, top and left side perspective view of a stand for a knitting machine or similar article showing my new design,

FIG. 2 is a rear top and right side perspective view,

FIG. 3 is a top plan view,

FIG. 4 is a left side elevational view,

FIG. 5 is a front elevational view,

FIG. 6 is a right side elevational view,

FIG. 7 is a bottom plan view, and

FIG. 8 is a rear elevational view.

This is a continuation-in-part of design application Ser. No. 339,814, filed Mar. 9, 1973, now abandoned.

I claim:

The ornamental design for a stand for a knitting machine or similar article, as shown and described.
